[57] CLAIM

The ornamental design for a rear view mirror, substantially as shown and described.

DESCRIPTION

FIG. 1 is a front perspective view of a rear view mirror showing my new design;

FIG. 2 is a left side elevational view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a rear perspective view thereof; and

FIG. 8 is a fragmentary side elevational view of a rear view mirror showing a second embodiment of my new design in which the only difference resides in the thinner mirror element retaining edge wherein the mirror element extends slightly forward of said retaining edge as illustrated herein.

FIG. 1.**FIG. 2.****FIG. 5.****FIG. 6.**

FIG. 7.

FIG. 8.

FIG. 3.

FIG. 4.
